(57) **CLAIM**

The ornamental design for an inflatable packing material, as shown and described.

DESCRIPTION

FIG. 1 is an isometric view of an inflatable packing material, showing our new design in a non-inflated condition;

FIG. 2 is a top view thereof, the bottom being a mirror image;

FIG. 3 is an isometric view of the inflatable packing material of FIG. 1, shown in an inflated condition;

FIG. 4 is an enlarged detail view thereof of area 4 circumscribed within FIG. 3;

FIG. 5 is a top plan view of the inflatable packing material of FIG. 1 as shown in FIG. 3, the bottom view is a mirror image;

FIG. 6 is a top plan view thereof showing isolated the solid lines of the claim;

FIG. 7 is a left side view thereof;

FIG. 8 is a right side view thereof;

FIG. 9 is a front view thereof; and,

FIG. 10 is a rear view thereof.

In the drawings, the dash-dash broken lines and the areas immediately surrounding the solid lines depict portions of the inflatable packing material that form no part of the claimed design. The dot-dash-dot broken lines within FIG. 3 and surrounding FIG. 4 indicate the detail area and form no part thereof.
